WILLIAM G. HILLEGASS, OF PHILADELPHIA, PENNSYLVANIA.

Letters Patent No. 70,840, dated November 12, 1867.

IMPROVEMENT IN PENCIL-HOLDERS FOR COMPASSES.

The Schedule referred to in these Letters Patent and making part of the same.

TO ALL WHOM IT MAY CONCERN:

Be it known that I, W. G. HILLEGASS, of Philadelphia, in the county of Philadelphia, and State of Pennsylvania, have invented a new and improved Pencil-Holding Attachment for Carpenters' Compasses; and I do hereby declare that the following is a full, clear, and exact description thereof, which will enable others skilled in the art to make and use the same, reference being had to the accompanying drawings, forming part of this specification.

The drawing represents a perspective view of my improved pencil-holder.

This invention relates to a device by which carpenters' steel-pointed compasses can be provided with a pencil-point whenever desired, so that the said pencils can be applied in a convenient manner, while heretofore the pencil had to be tied to one of the legs of the compass by means of a thread or string.

The invention consists in the use of two plates, which are so stamped that when they are laid together two tubes will be formed, of which one is fitted around one leg of the compass, while in the other the pencil is held. By means of a set-screw the two plates can be clamped together, so as to be firmly fitted around any one part of the leg, and so as to hold pencils of various thickness. This device can be easily applied and as easily removed, and will prove of great value to carpenters and mechanics in general.

A represents a metal compass, of ordinary construction. B B are two sheet-metal plates, stamped so as to form two tubes, *a* and *b*, when laid together. The same are held together by means of a thumb-screw, *c*, by which the diameter of the tubes may be enlarged or contracted. One of the legs of the compass fits through the tube *a*, while the pencil *C* is fitted through the tube *b*. The set-screw clamps the parts in any desired position.

I do not wish to confine myself to the special construction of the clamp B, as the same is herein shown. The same would operate as well if it were made of one piece only.

I claim as new, and desire to secure by Letters Patent—

The removable pencil-holding attachment for carpenters' compasses, the same consisting of the clamp B, made adjustable by a set-screw, *c*, substantially as and for the purpose herein shown and described.

WILLIAM GEO. HILLEGASS.
